UNITED STATES PATENT OFFICE.

JAMES L. PATTERSON, OF CHICAGO, ILLINOIS, ASSIGNOR TO UNION
SPECIAL SEWING MACHINE COMPANY, OF CHICAGO, ILLINOIS, A
CORPORATION OF ILLINOIS.

SEAM FOR SEWED ARTICLES.

SPECIFICATION forming part of Letters Patent No. 691,568, dated January 21, 1902.

Application filed March 5, 1901. Serial No. 49,723. (No model.)

To all whom it may concern:
Be it known that I, JAMES L. PATTERSON, a citizen of the United States, residing at Chicago, in the county of Cook, State of Illinois, have invented certain new and useful Improvements in Seams for Sewed Articles, of which the following is a description, reference being had to the accompanying drawings and to the characters of reference marked thereon.

My invention relates to an improvement in seams for sewed articles, the object of the same being to provide a lapped seam for garments in which the raw edge of the lower fabric is bound by suitable binding, the upper fabric having a hem fold, a row of stitches passing down through the upper fabric, its fold, and the lower fabric, and another row passing through the upper fabric, both edges of the binding, and the lower fabric, thus making a strong, durable, and ornamental seam; and the invention consists, primarily, in a seam for sewed articles comprising upper and lower lapped fabrics, one having an inwardly-turned hem fold and the other having a binding-strip folded around its edge, one edge of the binding-strip facing the inner edge of the hem fold, with means for securing the parts together; and the invention also consists in the matters hereinafter described, and referred to in the appended claims.

In the accompanying drawings, which illustrate the invention, Figure 1 is a top perspective view of a seam constructed in accordance with my invention, and Fig. 2 is a cross-section thereof.

In the drawings, A and B represent two pieces of fabric whose edges are to be united to form a durable, strong, and ornamental seam—as, for instance, on rain-coats, over-coats, and the like. The fabric A or upper piece of goods is provided with a turned-under portion *a*, while the lower fabric B is lapped by the folded edge of the fabric A. Through the two thicknesses of fabric A and the fabric B passes a row of stitches *l*. The raw edge of the lower fabric B is bound by a

strip of tape or other suitable binding *b*, the upper edge of the binding-strip facing the inner edge of the hem fold *a*, and a row of stitches *2* passes through the fabric A beyond the line of the fold, through the upper edge of the binding, the lower piece of fabric, and the lower edge of the binding, as shown. If desired, both edges of the binding *b* may be folded, as shown at *c*.

Preferably the seam is made upon a two-line sewing-machine of any well-known type, provided with a special construction of folding-guide, such as forms the subject-matter of an application filed by me of even date herewith, Serial No. 49,722, the upper fabric being folded, the raw edge of the lower piece bound, and the binding-pieces folded at the edges, and the parts being united, all in one continuous operation.

Having thus described my invention, what I claim, and desire to secure by Letters Patent, is—

1. The herein-described seam for sewed articles, comprising upper and lower lapped fabrics, one having an inwardly-turned hem fold and the other having a binding-strip folded around its edge, one edge of the binding-strip facing the inner edge of the hem fold, and means for securing the parts together; substantially as described.

2. The herein-described seam for sewed articles, comprising upper and lower lapped fabrics, one having an inwardly-turned hem fold, and the other having a binding-strip folded around its edge, one edge of the binding-strip facing the inner edge of the hem fold, and rows of stitching one of which rows of stitches passes through one fabric, its hem fold and the other fabric, and the other of which passes through both fabrics and both edges of the binding-strip; substantially as described.

3. The herein-described seam for sewed articles, comprising upper and lower lapped fabrics, one having an inwardly-turned hem fold, and the other having a binding-strip folded around its edge, said binding-strip having on each edge an inwardly-turned hem

fold, one edge of the binding-strip facing the inner edge of the hem fold, and rows of stitching, one of which rows of stitching passes through one fabric, its hem fold, and the other 5 fabric, and the other of which passes through both fabrics and both hem folds of the binding-strip; substantially as described.

In testimony whereof I affix my signature in presence of two witnesses.

JAMES L. PATTERSON.
